CONTROLLED ABSORBER COOLER IN
REFRIGERATOR

Curtis C. Coons, North Canton, Ohio, assignor to
The Hoover Company, North Canton, Ohio, a
corporation of Ohio

Application December 26, 1946, Serial No. 718,511

17 Claims. (Cl. 62—5)

1

The present invention relates to the art of refrigerating apparatus and more particularly to a new and improved refrigerating apparatus of the intermittent absorption type having a cooling system embodying a number of novel features.

It is customary to provide intermittent absorption refrigerating machines in two units which operate alternately with respect to each other on generating and absorbing periods of operation to provide substantially continuous refrigeration. Such systems have an inherent disadvantage in that the cooling jacket of the generator-absorber operating on the absorbing period of operation contains a considerable quantity of cooling liquid when it is switched over to generating operation. Such residual liquid in the cooling jacket must be driven out by vaporization due to the heat applied to the generator-absorber and thus represents a direct loss in heating effect.

It is a principal object of the present invention to provide a means so constructed and arranged as to pump the residual liquid in the generator-absorber cooling jacket out quickly as soon as heat is applied thereto without vaporizing more than a comparatively insignificant proportion of such residual liquid. By thus pumping out residual liquid, the thermal efficiency of the apparatus is directly increased and the generating period of the generator-absorber is decreased because it is no longer necessary to remove residual liquid by vaporizing the entire quantity thereof.

It is a further object of the present invention to eliminate the externally operated cooling medium control valve characteristic of conventional systems and to control the flow of cooling medium in heat exchange with the generator-absorber solely by the external application of heat to the generator-absorber.

It is a further object of the invention to provide a dual intermittent absorption refrigerating system so arranged that heat removed from one generator-absorber at the beginning of its heating period is utilized to aid the initial heating of an associated generator-absorber beginning a heating period of operation.

These and other objects of the invention will be developed in detail as the description proceeds when taken in connection with the accompanying drawing, in which:

Figure 1 is a diagrammatic representation of an intermittent absorption refrigerating machine embodying the present invention;

Figure 2 is a partial view of a modified form of the invention; and

Figure 3 is a similar view of another modification of the invention.

2

Referring now to Figure 1, two substantially identical intermittent absorption refrigerating machines are illustrated on the right and left hand sides of said figure, respectively. Since the two intermittent absorption refrigerating systems are identical, only the left-hand system in Figure 1 will be described directly and the parts of the right-hand system will be given the same reference characters as the corresponding parts in the left-hand system distinguished by a prime.

The primary refrigerating system consists of a generator-absorber assembly 1, a condenser 2, and an evaporator assembly 3. The generator assembly 1 communicates with the condenser through a vapor pipe 4 and the condenser communicates with the evaporator assembly 3 by a pipe 5.

The generator construction may be of any desired type in accordance with the principles of the present invention. For purposes of illustration the present invention is applied to the type of generator-absorber assembly which utilizes a dry salt such as strontium chloride as the absorbent. Anhydrous ammonia is a preferred refrigerant but this invention is not limited thereto. Briefly, the generator-absorber assembly 1 comprises an outer jacket or casing 7 and an inner concentrically arranged jacket or casing 8 between which are positioned a plurality of trays containing the absorbing medium such as strontium chloride, not shown. A third tube or conduit 9 arranged concentrically with the jacket 8 is secured thereto to form a cooling jacket 10 therebetween. The central heating tube 9 forms a products of combustion flue for the fuel burner 11 which discharges its products of combustion thereto.

The evaporator assembly may be of any desired type. However, for purposes of illustration herein the evaporator assembly is shown as of the type disclosed in United States Letters Patent 2,386,438.

The cooling jacket 10 formed by the space between the concentrically positioned cylinders 8 and 9 communicates at its upper end with a condenser 15 through a conduit 16. The condenser 15 discharges into a liquid receiver 17 from which the condensed cooling medium is conveyed to a control valve casing 18 through a conduit 19. The valve casing 18 encloses a control valve element 20 which directs the cooling medium into conduits 21 or 21' which communicate with the lower ends of the cooling jackets 10 and 10', respectively.

The lower end of the cooling jacket 10 also communicates with a vapor lift pump 23 extend-

ing upwardly through the products of combustion flue 9 and opens into an enlarged substantially horizontal conduit 24 which discharges into the receiver 17. The large air cooled conduits 24 and 24' promote condensation of vapor therein contained. The vertical portion of pump 23 is heated by the burner 11 simultaneously with the generator-absorber 1. The above described cooling system may be charged with any desired cooling medium; methyl chloride is an example of one suitable substance for this purpose.

Fuel is supplied to the apparatus through a gas supply conduit 25 which connects to the solenoid valves 26 and 26' which control the supply of fuel to the burners 11 and 11', respectively, through conduits 27 and 27', respectively. A constant flame pilot or ignition burner and pilot flame failure fuel shut off device 28 is mounted to receive fuel from conduit 25 at the point at which that conduit branches to supply fuel to the solenoid valves 26 and 26'. The structure 28 is a known type ignition flame and safety cut-off device which blocks all fuel supply to the unit if the pilot flame is extinguished. Flash tube igniters 12 and 12' extend from the pilot flame to a point adjacent to the burners 11 and 11' respectively. When fuel is supplied to either burner a portion of the escaping fuel travels thru the associated flash tube to the pilot and is ignited, the resulting flame propagates back thru the flash tube and ignites the burner.

A bulb and bellows thermostatic device 29 is responsive to the temperature of the external jacket 7 of the generator assembly 1. The expandable bellows is positioned to engage the actuating arm 30 of the control mechanism which actuates the valve 20. The control arm 30 is also positioned to actuate a double pole electrical switch 31. In the position shown, the switch 31 energizes the solenoid valve 26 to supply fuel to the burner 11. The valve 26 is energized from line wire 32, control switch 33, line wire 34, switch 31, wire 35, and line wire 36.

The cooling medium conduit 19 is provided with a snap-acting valve 38 which is linked to a thermostatic bellows 39 along with the electrical switch 33. The arrangement is such that expansion of the bellows 39 indicating a demand for refrigeration causes switch 33 to close the circuit between line wires 32 and 34 and valve 38 to open to allow cooling medium to flow from reservoir 17 to control valve chamber 18. This control mechanism is more fully described and illustrated in United States Letters Patent 2,410,-334 issued October 29, 1946.

Assuming a demand for refrigeration the valve 38 will be open and the switch 33 closed. Immediately after the actuating arm 30 has been moved to the left by expansion of the thermostatic structure 29' and valve 20 has closed conduit 21—the condition illustrated—cooling medium flows from chamber 18 through conduit 21' into jacket 10'. Switch 31 has also energized solenoid valve 26 to provide a full supply of gas to burner 11. Burner 11 is shown immediately after full energization thereof, that is, discharging products of combustion through the combustion flue 9 and in contact with the pump conduit 23. At this time the jacket 10 contains a considerable quantity of liquid cooling medium at a temperature approaching that of the atmosphere. Unless removed from the jacket 10, such residual liquid will be entirely vaporized by the heat supplied from burner 11, resulting in an appreciable waste of thermal energy.

In accordance with the present invention, the heat of the flame on burner 11 vaporizes a small portion of the liquid in conduit 23. Such vapor lightens the liquid column in conduit 23 and produces a vapor lift pump action which pumps the liquid and such vapor as is formed through conduit 23 into the enlarged conduit 24. The vapor and liquid separate in conduit 24 and both then flow into the vessel 17. Residual liquid in jacket 10 is quickly pumped into the receiver 17 and can then participate in the process of cooling the generator-absorber structure 1'.

The apparatus continues to operate in the usual manner, that is, the heat applied to the generator-absorber assembly 1 drives refrigerant vapor from the absorbent, which vapor traverses conduit 4, is liquefied in condenser 2, and collects in the left-hand evaporator assembly 3. At the same time, cooling liquid flows from reservoir 17 into the cooling jacket 10' wherein the same is vaporized and cools the absorbent in the generator-absorber 1'. The cooling medium vapor then flows from jacket 10' through conduit 16' into condenser 15' wherein it is reduced to the liquid state and returns to the reservoir 17 for recirculation through the jacket 10'. Any vapor which passes into condenser 15 will be condensed therein and the condensate will flow into reservoir 17.

The cooling medium serves to reduce the temperature of the absorbent in the generator-absorber 1' very quickly with the result that the pressure in the primary system is rapidly lowered which induces evaporation of the liquid refrigerant contained in evaporator 3' to produce a useful refrigerating effect. The vapor produced in evaporator 3' returns through conduit 5', condenser 2', conduit 4', to the generator-absorber assembly 1', wherein it is reabsorbed.

When the temperature of the generator-absorber 1 reaches a preselected elevated value, the bellows 29 will expand from the position shown and actuate the arm 30 to its operative position. Such operation will shift valve 29 to discontinue supply of cooling medium to the cooling jacket 10' and to allow the supply of cooling medium to the jacket 10. Additionally, the switch 31 will be actuated to de-energize the solenoid valve 26 and to energize solenoid valve 26'; this extinguishes burner 11 and supplies fuel to the burner 11' which ignites from the pilot structure 28. The bellows 29' will be collapsed, that is, in the condition shown for bellows 29, long prior to the time at which the bellows 29 is expanded by the attainment of a predetermined high temperature in the generator-absorber 1 and will not interfere with movement of arm 30 by bellows 29. Upon such switchover the cooling jacket 10' is then emptied of residual liquid in the manner above described for the cooling jacket 10.

Whenever the control switches a generator-absorber from heating to cooling operation, a considerable quantity of cooling medium flows into the very hot (approximately 300° F.) cooling jacket of the previously heated generator-absorber. High temperature vapor in large quantities is immediately produced. The resulting rush of vapor will overtax the condensers 15 and 15' with the result that vapor will condense in the cooling jacket of the generator-absorber just starting a heating period of operation and aid in the initial heating of the cold generator-absorber. This condensate is then pumped by pump 23 or 23' into reservoir 17. The above mentioned con-

densation in the cooling jacket increases the thermal efficiency of the system by transferring heat from the hot generator-absorber starting a cooling period to the cold generator-absorber starting a heating period.

A modified form of the invention is illustrated in Figure 2. Since the primary system of this form of the invention is identical with that illustrated in connection with Figure 1, illustration thereof is omitted from Figure 2. The control mechanism for the Figure 2 form of the invention is also identical with the control mechanism of the Figure 1 form of the invention except that, as will hereinafter appear, it will not contain valve means for regulating the flow of the secondary cooling medium. The control mechanism is also omitted from Figure 2 for clarity in illustration. Since the major portion of the invention in Figure 2 is identical with that heretofore described in connection with Figure 1, identical parts are given the same reference characters.

In the Figure 2 form of the invention, referring first to the left-hand generator-absorber 1, the cooling jacket 10 is connected with a condenser 15 by a conduit 16. The condenser discharges through a conduit 40 into a cooling medium reservoir 41. The cooling medium reservoir is internally divided along its bottom wall by a partition 41 into right- and left-hand chambers and is jacketed with insulating material 42. The left- and right-hand sides of the reservoir 41 drain into the bottom portions of jacket 10' and 10, respectively, by means of conduits 43' and 43, respectively. In this form of the invention a vapor lift pump 45—generally corresponding to vapor lift pump 23 of Figure 1—communicates with the conduit 43 at a low point thereof and closely adjacent its point of connection with jacket 10. Vapor lift pump 45 extends upwardly through the heating flue 9 so as to be heated by products of combustion discharged from the burner 11 and discharges into an enlarged conduit 44 which empties into the reservoir 41 on the left-hand side of partition 41. Similarly the vapor lift pump 45' extends through flue 9' and discharges into an enlarged conduit 46 which empties into the reservoir 41 on the right-hand side of partition 41.

A tilt bucket structure 48 is tiltably mounted on the upper edge of the dividing partition wall 47. This structure is provided with left- and right-hand bucket chambers 49 and 50, respectively, arranged to discharge into conduits 43' and 43, respectively, when properly tilted. A directing trough 52 is rigidly mounted upon the upper end of the tilt bucket structure 48 directly beneath the open end of conduit 40.

The arrangement is such that liquid discharging from conduit 40 in the position shown, for example, flows across the directing plate 52 and discharges into conduit 43 to flow into the cooling jacket of the generator-absorber 1.

The apparatus as illustrated is in the condition which it will assume immediately after the burner 11' has been de-energized and burner 11 has just achieved full flame operation. At this time the generator-absorber assembly 1 is cold and the jacket 10 contains a large quantity of cold cooling medium. The heat applied, however, to the vapor lift pump conduit 45 will pump liquid contained in jacket 10, and such liquid as may at that time flow toward jacket 10 through conduit 43, into the reservoir 41 and will discharge into the bucket 49 of the tilt bucket structure 48.

Liquid discharged into tilt bucket 49 will quickly over-balance the tilt bucket structure, causing it to tip to a position opposite to that shown, at which time liquid in the bucket chamber 49, liquid discharging through vapor lift pump 45, and liquid discharging through conduit 43' will all flow into conduit 43' and thence to the generator-absorber 1' which has just completed a heating period of operation.

10 The sudden discharge of a considerable quantity of cold liquid cooling medium into jacket 10' of generator-absorber 1' will produce a rush of vapor. Vapor will condense in the still cold cooling jacket 10 of the generator 1. As described 15 above in connection with the Figure 1 form of the invention and, as before, vapor condensed in jacket 10 will immediately be pumped back into the reservoir. Liquid condensed in condensers 15 and 15' will, however, flow through conduit 40 and will return to the cooling jacket 10'.

20 After initial stabilization of conditions in the system and emptying of jacket 10 of cooling medium, there will be no further discharge through vapor lift pump 45 and condensate formed in the secondary condenser system will flow back into the jacket 10' to continue cooling the generator-absorber assembly 1'.

25 When the control mechanism de-energizes burner 11 and re-energizes burner 11', the reverse 30 of the foregoing steps in the operation of the apparatus will then occur.

In this form of the invention the control need act only on the energy supply or fuel supply for the heating means for the generator-absorbers.

35 The cooling medium is directed to the desired cooling jacket solely by operation of heat operated means placed in operation in response to the energization of one or the other of the heaters for the generator-absorbers. This form of the 40 invention combines the desirable feature of positively pumping residual liquid out of the cooling jacket of the generator-absorber immediately it is switched from cooling to heating operation with a construction which utilizes the liquid so discharged to direct the cooling medium in the system into the cooling jacket of the generator-absorber just switched from heating to cooling operation.

45 Referring now to Figure 3, there is illustrated a 50 third modification of the invention. Since the primary system of Figure 3 is identical with that of Figure 1, only the generator assembly has been shown. Likewise the control for the fuel burners is also identical with that of Figure 1 and has also been omitted in Figure 3 for clarity, though the Figure 3 construction, like that of Figure 2, does not include a valve mechanism for controlling the flow of cooling medium to the generator-absorber. Those portions of the apparatus of Figure 3 which are identical with constructions previously described in connection with Figure 1 are given the same reference characters for simplification.

55 In this form of the invention, cooling jacket 10 60 communicates with an air-cooled condenser 15 by means of a conduit 16. Condensate formed in condenser 15 is conveyed to the bottom portion of jacket 10 through a conduit 69. The condensers 15 and 15' are positioned laterally adjacent each other and are provided with common fins for a reason to be hereinafter developed.

65 The vapor lift pump conduits 23 and 23' for 70 removing residual liquid from jackets 10 and 10', respectively, discharge into enlarged vapor and liquid separating chambers 62 and 65, respec-

tively, which empty into reservoir chambers 61 and 64, respectively. The enlarged conduits 62 and 65 are exposed to cooling air and aid in condensing vapors therein contained. Liquid discharged into chamber 61 is drained therefrom into the upper portion of jacket 10' by a conduit 63 which contains a U-shaped liquid sealing trap. Similarly, conduit 23' discharges into a vessel 64, which communicates with the cooling jacket 10 through a conduit 66 containing a U-shaped liquid trap. The vessels 61 and 64 are formed in a single container having a dividing partition therein. Vessels 61 and 64 communicate with each other through the opening 67 in the partition above the highest liquid level attained in these vessels. These vessels are preferably arranged to be air cooled to aid in condensing pumping vapor discharging thereinto.

The operation of the form of the invention of Figure 3 is as follows: Assuming that heat has just been applied to the generator 1 by energizing burner 11, liquid in conduit 23 will be partially vaporized and will start to pump liquid from jacket 10 through pump 23, and conduit 62 into vessel 61. Liquid thus discharged into the vessel 61 will flow through conduit 63 into the jacket 10'. The generator-absorber assembly 1' has just completed a heating period of operation and is at a very high temperature. Liquid flowing into jacket 10' is immediately vaporized and a high pressure is created throughout the cooling system associated with the generator-absorber 1'. This high pressure is also applied to the cooling system of the generator-absorber 1 through conduit 63, vessel 61, opening 67, and conduit 66. This action empties the trap in conduit 66 and will, momentarily, stall operation of the vapor lift pump 23. The high pressure will also push liquid in jacket 10 up into conduits 16 and 60 in the direction of condenser 15 until pressure equalization occurs.

Shortly after this equalization of pressure, the pump 23 will again go into operation and will continue to pump liquid from jacket 10 into jacket 10'. Pumping vapor is partly condensed in conduit 62 and pumping vapor reaching chamber 61 is condensed in chambers 61 and 64, and in conduit 65. Vapor condensing in chamber 61 and conduit 62 flows into the cooling jacket 10' but vapor condensing in chamber 64 and conduit 65 will first refill the trap in conduit 66 to replace liquid forced into cooling jacket 10 when initial high pressure conditions were produced by the initial supply of cooling medium to the hot jacket 10'. Any condensate returning to jacket 10 is repumped into chamber 61.

After the initial unstable conditions are restored by pressure equalization, the jacket 10' will be sealed from the cooling system of generator-absorber 1 by the deep trap in conduit 63: that is, vapor formed in cooling jacket 10' will flow through conduit 16' into condenser 15', and condensate formed therein will return to jacket 10', thus achieving isolation of the two cooling systems. This isolation is not defeated by the vapor lift pump 23' because the pump is in the central flue of the generator-absorber 1' and will be at a lower temperature than that prevailing in jacket 10' and hence liquid in the pump will not tend to vaporize.

The basic factor preventing transference of vapor between the two cooling systems in addition to the trap in conduit 63 is the fact that the two condensers are in heat exchange relation. Vessels 61 and 64 will be at substantially the same temperature. The parts of the cooling system of

the generator-absorber 1 which are closely associated with the generator itself, will be at a temperature far above the condensing temperature for the pressure prevailing in the cooling system of generator-absorber 1'. Hence there will be no tendency for vapor to travel from conduit 23 and condense in these portions of the cooling system. Additionally, the condensers 15 and 15' will very quickly reach substantially the same temperature; hence there will be no tendency for vapor to travel through the cooled conduit 65, vessel 64, conduit 66, jacket 10, into the condenser 15 to condense therein. Consequently, after an initial slight exchange of vapor between the systems, further vapor exchange will cease and the systems will be effectively isolated from each other.

Under the above conditions, the condenser 15 may actually exist at a somewhat lower temperature than condenser 15' without inducing a flow of vapor thereinto from the cooling system of the generator-absorber 1'. This results from the fact that the liquid in conduit 23' and in conduit 63 or vessel 61 is stagnant and air-cooled, and hence will be at a temperature somewhat below the temperature prevailing in the condenser 15'. In short, the system quickly stabilizes itself to a point at which all the liquid in the cooling system is in that part of the system specifically associated with generator-absorber 1', and all liquid surfaces open to that part of the cooling system specifically associated with the generator-absorber 1 are stagnant, air-cooled, and at a temperature below that of condenser 15'.

It is characteristic of all forms of the invention that liquid is quickly pumped from the generator-absorber which has just completed an absorbing period when heat is applied thereto and that the liquid so pumped out of the heated generator-absorber flows directly into the generator-absorber which has just completed a heating period.

In addition to the above, the forms of the invention illustrated in Figures 2 and 3 shift the cooling action from one system to the other without the intervention of externally actuated parts so that the control mechanism is required to act directly solely upon the energy source for the generator-absorbers. This results in a material saving of parts and simplification of operation of the system.

It is also characteristic of all forms of the invention that heat is transferred from the hot generator-absorber which has just completed a heating period of operation to the cold generator-absorber which has just completed a cooling period of operation by vapor passing from the hot generator-absorber and condensing in the cool generator-absorber.

Though the means specifically disclosed herein for emptying the generator-absorber cooling jackets consists of a heat operated pump of the vapor lift type other types of pumping means for accomplishing this purpose are within the scope of my invention. For example electric motor driven pumps in which the electric motor receives its energy from a thermo-pile heated by the generator-absorber heater or electric motor driven pumps in which the electric motors are connected in parallel with the solenoid valves for the associated generator-absorber heater to be energized simultaneously therewith may be utilized in place of vapor lift pumps.

While the invention has been illustrated and described in detail it is not to be limited thereto

but various changes may be made in the construction, design and arrangement of parts without departing from the spirit of the invention or the scope of the appended claims.

I claim:

1. In a refrigerating apparatus a generator-absorber, a cooling system for said generator-absorber having a heat absorbing part in heat exchange relation with said generator-absorber and a heat rejecting part, means connecting said heat rejecting and heat absorbing parts for circulation of cooling fluid therebetween, a vapor lift pump connected to receive cooling liquid from said heat absorbing part and to pump cooling medium from said heat absorbing part to another part of said cooling system, means for heating said generator-absorber and said pump, and means for simultaneously energizing said heating means and for preventing flow of cooling medium from said another part of said cooling system into said heat absorbing part.

2. In a refrigerating apparatus a pair of generator-absorbers, means for applying heat to each of said generator-absorbers, a cooling system having heat absorbing means in heat exchange relation with each of said generator-absorbers, heat rejecting means, means providing paths of flow for cooling medium including said heat absorbing means and said heat rejecting means for each of said generator-absorbers, means associated with said cooling system for pumping liquid cooling medium from the heat absorbing means in heat exchange with the generator-absorber being heated into the path of flow of cooling medium flowing to the heat absorbing means in heat exchange relation with the unheated generator-absorber, and means controlling the operation of said heating means and said pumping means for heating said generator-absorbers alternately and for pumping cooling medium out of the heat absorbing means in heat exchange relation with the heated generator-absorber.

3. In an absorption refrigerating apparatus of the intermittent type, a generator absorber, means associated with said generator-absorber for passing a coolant in heat exchange relation therewith, heat rejecting means connected to receive warm coolant from said coolant passing means, means for conveying coolant from said heat rejecting means, to said coolant passing means, means for interrupting the flow of coolant to said passing means when heat is applied to said generator-absorber, means for intermittently heating said generator-absorber, heat operated pumping means connected to receive coolant from said passing means and to discharge coolant to a portion of the apparatus from which such coolant can return to said passing means only through said interrupting means, and means for heating said generator-absorber and said pumping means simultaneously.

4. In an absorption refrigerating apparatus a pair of generator-absorbers, heating means for heating said generator-absorbers alternately, a cooling system having heat absorbing parts in heat exchange relation with said generator-absorbers, heat rejecting means arranged to receive warm coolant from said heat absorbing parts, means for conducting cooled coolant from said heat rejecting means to said heat absorbing means including means to direct such cooled coolant to the heat absorbing part associated with the generator absorber not being heated by said heating means, heat operated pumping

means associated with each generator-absorber positioned to be heated simultaneously with said generator-absorber and connected to pump coolant from said heat absorbing parts to a part of the apparatus from which such coolant can flow to said heat absorbing parts only through said directing means.

5. In an absorption refrigerating apparatus a pair of generator-absorbers, heating means for heating said generator-absorbers alternately, a cooling system having heat absorbing parts in heat exchange relation with said generator-absorbers, heat rejecting means arranged to receive warm coolant from said heat absorbing parts, a reservoir connected to receive coolant from said heat rejecting means, conduits for conducting coolant from said reservoir to each of said heat absorbing parts, movable means in said reservoir for directing coolant from said heat rejecting means into the conduit leading to a selected one of said heat absorbing parts, a heat operated pumping means associated with each of said generator-absorbers and each arranged to be heated when heat is applied to the associated generator-absorber, fluid operated means in said reservoir for operating said movable means, each of said heat operated pumps discharging into said reservoir to operate said fluid operated means and to discharge fluid pumped from one heat absorbing part into the conduit leading to the other heat absorbing part.

6. In an absorption refrigerating apparatus a pair of generator-absorbers, heating means for heating said generator-absorbers alternately, a cooling system having heat absorbing parts in heat exchange relation with said generator-absorbers, heat rejecting means arranged to receive warm coolant from said heat absorbing parts, a reservoir connected to receive coolant from said heat rejecting means, conduits for conducting coolant from said reservoir to each of said heat absorbing parts, a tiltable structure in said reservoir having two liquid receiving pockets each arranged to overbalance said structure and to discharge liquid therein when a predetermined quantity of liquid has been collected in the pocket, said conduits being connected to said reservoir in such manner that each conduit receives liquid from one of said pockets, a diversion element arranged to be operated by said tiltable structure to direct coolant entering said reservoir into the conduit into which said tiltable structure is positioned to discharge, a vapor lift pump associated with each generator-absorber and arranged to be heated therewith, each vapor lift pump being connected to remove coolant from the heat absorbing part of the associated generator-absorber and discharge coolant into the pocket of said tiltable structure which discharges accumulated liquid into the heat absorbing part of the other generator-absorber.

7. In an absorption refrigerating apparatus a pair of generator-absorbers, heating means for heating said generator-absorbers alternately, a cooling system having heat absorbing parts in heat exchange relation with said generator-absorbers, heat rejecting means arranged to receive warm coolant from said heat absorbing parts, and to return cooled coolant to the heat rejecting part of origin, a vapor lift pump associated with each generator-absorber and arranged to be heated therewith, each of said vapor lift pumps connected to receive coolant from the heat absorbing part in heat exchange relation with the associated generator-absorber and to discharge

coolant into the heat absorbing part in heat exchange relation with the other generator-absorber.

8. Absorption refrigerating apparatus comprising a pair of generator-absorber assemblies each including an absorbent container, a heat absorbing part for cooling medium in heat exchange relation with said container, a vapor lift pump connected to the lower part of said heat absorbing part and a heating means arranged to heat said pump and said container, a heat rejecting means connected to each of said heat absorbing parts to form a cooling medium circuit individual to each generator-absorber assembly, each of said vapor lift pumps being connected to 15 discharge cooling medium from the cooling medium circuit of the associated generator-absorber into the cooling medium circuit of the other generator-absorber.

9. Absorption refrigerating apparatus comprising a pair of generator-absorber assemblies each including an absorbent container, a heat absorbing part for cooling medium in heat exchange relation with said container, a vapor lift pump connected to the lower part of said heat absorbing part and a heating means arranged to heat said pump and said container, a heat rejecting means connected to each of said heat absorbing parts to form a cooling medium circuit individual to each generator-absorber assembly, each of 30 said vapor lift pumps being connected to discharge cooling medium from the cooling medium circuit of the associated generator-absorber into a reservoir, and a connection from said reservoir to the heat absorbing part of the other generator-absorber assembly including a liquid sealed trap.

10. In an absorption refrigerating apparatus comprising a pair of intermittent absorption refrigerating systems each including a generator-absorber, a condenser and an evaporator connected in circuit; heating means for heating said generator-absorbers alternately; vaporization-condensation cooling means having parts in heat exchange relation with said generator-absorbers including vapor lift pumping means associated with each generator-absorber arranged to be heated therewith, each of said vapor lift pumping means being connected to pump liquid cooling medium from parts of said vaporization-condensation cooling means in heat exchange relation with its associated generator-absorber into parts of said vaporization-condensation cooling system from which such liquid can flow into heat exchange relation with the other generator-absorber.

11. Refrigerating apparatus comprising a pair of generator-absorbers, heating means, a cooling system including heat absorbing parts in heat transfer relation with each generator absorber and heat rejecting means, pump means connected to receive liquid cooling medium from said heat absorbing parts and to discharge liquid cooling medium received from one heat absorbing part into a part of the cooling system from which the cooling medium can flow into the other heat absorbing part, and control means for actuating said heating means to apply heat alternately to said generator absorbers and to actuate said pumping means to remove liquid cooling medium from the heat absorbing part associated with the heated generator absorber.

12. Refrigerating apparatus comprising a pair of intermittent refrigerating systems each including a generator-absorber, a cooling means for each generator-absorber, each of said cool-

ing systems including a heat absorbing part arranged to cool the associated generator-absorber and a heat rejecting part connected in circuit for circulation of a cooling medium, means associated with each generator-absorber arranged to pump liquid cooling medium from the cooling means of the associated generator-absorber into the cooling system of the other generator-absorber, means for heating said generator-absorbers, and means for activating the heating means and the pumping means for each generator-absorber alternately with respect to the heating and pumping means for the other generator-absorber to apply heat thereto and to pump cooling medium into the cooling system of the associated generator-absorber.

13. In a refrigerating system; a pair of intermittent absorption refrigerating apparatuses each comprising a generator absorber, a condenser and an evaporator connected in circuit; means for individually heating said generator-absorbers; a cooling system for said generator-absorbers including a plurality of communicating parts, said parts including a heat absorbing part in heat exchange relation with each generator-absorber, a condensing part connected to receive coolant vapor from said heat absorbing parts, coolant liquid directing means for directing the liquid coolant in the system into a selected one of said heat absorbing parts including pump means arranged to withdraw liquid coolant from the part in heat absorbing relation with each generator-absorber and to pump such withdrawn liquid coolant into a part of the system from which it can flow into the part in heat absorbing relation with the other generator-absorber, and means for activating the pumping means and the heating means to apply heat to each generator-absorber and to pump coolant from the heat absorber part associated with the heated generator-absorber alternately.

14. Refrigerating apparatus comprising a pair of intermittent absorption refrigerating apparatuses each including a generator-absorber; means for heating said generator-absorbers alternately, a cooling system for cooling each of said generator-absorbers alternately including a vaporizing part in heat exchange relation with each generator-absorber, a condensing part associated with each vaporizing part arranged to receive coolant vapor therefrom and to return liquid coolant into said vaporizing part, a heat operated pumping means associated with each generator-absorber and arranged to be heated therewith, each pumping means being connected to receive liquid coolant from the cooling system of the associated generator-absorber and to pump liquid coolant into the cooling system of the other generator-absorber.

15. In a refrigerator, a generator-absorber, a cooling system for said generator-absorber including a heat absorbing part in heat exchange relation with said generator-absorber, a heat rejecting part, means for conveying heated cooling medium from said heat absorbing part to said heat rejecting part, means for conveying cooling medium from said heat rejecting part to said heat absorbing part including flow control means for allowing or preventing flow of cooling medium into said heat absorbing part, a vapor lift pump connected to receive liquid cooling medium from said heat absorbing part and to discharge cooling medium into a part of the system from which it flows toward said flow control means, and means for simultaneously heat-

ing said generator-absorber and said vapor lift pump.

16. Refrigerating apparatus including a pair of generator-absorbers, means for heating said generator-absorbers alternately, a cooling system associated with said generator-absorbers including a pair of heat absorbing parts each of which is in heat exchange with a different one of said generator-absorbers, heat rejecting means arranged to receive cooling medium vapor from said heat absorbing parts and to return liquid cooling medium to said heat absorbing parts, said system including means for directing liquid cooling medium from said heat rejecting means into the heat absorbing part in heat exchange with the generator-absorber which is not being heated, a pair of vapor lift pumps each arranged to receive liquid cooling medium from the heat absorbing part in heat exchange with a different one of said generator-absorbers and to be heated simultaneously with the generator-absorber in heat exchange with the heat absorbing part from which it receives cooling medium, said vapor lift pumps discharging liquid cooling medium into parts of said system from which it flows to the heat absorbing part in heat exchange with the generator-absorber which is not being heated.

17. Absorption refrigerating apparatus comprising a pair of intermittent refrigerating systems each including a generator-absorber, means for heating said generator-absorbers alternately, a cooling system for said generator-absorbers comprising a pair of heat absorbing parts each

arranged to cool a distinct one of said generator-absorbers, heat rejecting means arranged to receive heated cooling medium from said heat absorbing parts, means for conveying cooled cooling medium from said heat rejecting means to said heat absorbing parts into either of said heat absorbing parts, a heat operated pumping means associated with each of said heat absorbing parts and arranged to pump liquid cooling medium from its associated heat absorbing part into said conveying means and to be heated simultaneously with the generator-absorber in heat exchange with its associated heat absorbing part and means in said conveying means operated by liquid discharged by either of said pumping means for directing liquid discharged from said heat rejecting means and said pumping means into the heat absorbing part associated with the non-operating pumping means.

CURTIS C. COONS.
